UNITED STATES PATENT OFFICE.

WILLIAM GOLDIE, OF WILKINSBURG, PENNSYLVANIA.

APPARATUS FOR FORMING SEATS IN RAILROAD-TIES.

SPECIFICATION forming part of Letters Patent No. 758,525, dated April 26, 1904.

Application filed January 8, 1903. Serial No. 138,267. (No model.)

To all whom it may concern:

Be it known that I, WILLIAM GOLDIE, a resident of Wilkinsburg, in the county of Allegheny and State of Pennsylvania, have invented a new and useful Improvement in Apparatus for Forming Seats in Railroad-Ties; and I do hereby declare the following to be a full, clear, and exact description thereof.

My invention relates to the cutting of seats or kerfs in railroad cross-ties to receive the rails, its object being to provide for the cheap laying of new track to exact gage or for the relaying of old rails or for reinforcements of the same, such as when it is desired to stiffen the track by the employment of supporting base-bars or bridge-pieces or for bringing the track itself to perfect alinement or surface. In applications filed November 19, 1902, Serial Nos. 131,918, 131,919, and 131,920, relating to railroad-tracks, rail structures, and rail-joints, one of the features described is the formation in the cross-ties of transversely-extending seats with grooves or kerfs to receive either bridge-pieces placed under the rails at the joints or supporting base-bars extending continuously under the rails, such bridge-pieces or base-bars having longitudinally-depending supporting ribs fitting into such grooves or kerfs in the ties or rails themselves provided with such longitudinally-supporting ribs formed under the flange.

The present invention relates to apparatus for laying tracks embodying these inventions, as well as for laying tracks with the ordinary rails, where it is desired to bring the track to more perfect surface, to accomplish this work cheaply, and to obtain a practically perfect gage or surfacing of the track.

To these ends my invention consists, generally stated, in apparatus for cutting seats for the rails in the cross-ties provided with rotary cutting mechanism guided by one or both of the rails, so that in the use of the apparatus through the guidance of the rails seats or seats and kerfs may be cut in the ties in exact alinement with the rails and of depth gaged by the height of the rails, a simple and efficient means for forming such seats either for the seating of ordinary railroad-rails or the tie-plates employed therewith or for the

seating of the rail structures having depending ribs or of bridge-pieces for rail-joints being thus obtained.

It also comprises a car in which such apparatus is mounted, the details of which car will be hereinafter described.

To enable others skilled in the art to make and use my invention, I will describe the same more fully, referring to the accompanying drawings, in which—

Figure 1 is a side view of the apparatus, illustrating the invention. Fig. 2 is a top or plan view showing some of the parts in dotted lines. Fig. 3 is a cross-section on the line 3-3, Fig. 1; and Figs. 4, 5, and 6 illustrate the different forms of seats and rails fitting in the seats which may be formed by the apparatus embodying the invention.

In an application of even date herewith, Serial No. 138,266, I have described the method of forming such kerfs or seats in the ties and manipulating the rails to provide for either resurfacing of the track or relaying of the same with or without supporting base-bars, so that a detail description of the method involved is not considered necessary in this application. As set forth in said application, the purpose of the apparatus is to form in the ties 2 seats 3, which preferably have grooves or kerfs 4 cut in the base thereof to receive the ribs 5 of the supporting base-bars 6 under the rails 7, the seats 3 generally being formed of slight rabbets planed or cut in the top surface of the tie and the grooves or kerfs 4 being formed in the base thereof when necessary.

As described in the above applications for patent, by means of the supporting base-bars seated in the seats 3 the rails themselves are properly supported throughout their length where a continuous base-bar is employed or supported at the joints where the base-bar is employed at that point, and the depending ribs either on the base-bars, as illustrated in Fig. 4, or on the rails themselves, as illustrated in Fig. 5, by being seated in the kerfs and seats provided in the cross-ties are held to exact gage, all liability of the spreading of the track being prevented. It is of course important in the laying of such track and in the forming of the kerfs or grooves in the cross-ties that the seats

to receive the rail shall conform exactly to the curves of the track itself, and where, as with the present apparatus, the track previously laid is employed as a guide for the laying of 5 the new track or for the formation of seats to arrange for the temporary shifting of old track in connection with the laying of new track it is extremely important that the apparatus be arranged to follow all the curves 10 of the old track and to cut seats at exact distance from the old track, so that when the track is properly relaid according to the system with which this apparatus is employed and as described in the companion application, Serial No. 138,266, covering the method, 15 the track shall be brought to exact alinement and to proper height of track without disturbing the cross-ties as they are laid. For this purpose I provide the apparatus shown 20 in the accompanying drawings, which illustrate the preferable form of machine for accomplishing the result, though it is to be understood that any suitable apparatus embodying the features herein claimed is included. 25 I have illustrated the invention in connection with the car 9, carrying a cutter-shaft provided with rotating cutters 10 and 11, adapted to cut the seats 3, with or without the kerfs 4, in the ties 2 at the sides of the 30 rails. The car illustrated has the boiler 12 and the engine 13, from which connections are made in any suitable way, such as by the sprocket-chain 14, with the engine-shaft to one of the wheels 15 of the main truck 16 of the car. I prefer to provide the car, as shown, 35 with two trucks 16 and 17 and to form the car-body of two sections 18 and 19, pivoted together, as at 20, and to provide the main section 18 with the depending frame 21, carrying the grooved guide-wheel 22, running on the track and forming the guide for the rotating cutters, so as to arrange to form the seats in proper alinement with the track. I 40 prefer to employ only one such grooved guide-wheel on the frame, the other supporting-wheel 23 of the frame 21 being plain-faced and simply acting as a support for the cutter close to the same and to regulate the depth of cut of the seat or kerf formed in the tie by that cutter. 45 By providing the car with the hinge 20 it is evident that the main section 18 may through the wheels 22 and 23 follow the course of the track, and so hold the cutters 10 and 11 in proper alinement therewith during their cutting action. Power is carried 50 by suitable chains or belts 24 25 to the cutter-shaft 26, carrying the cutters 10 11 and mounted to slide in the frame 21, the descent of the cutters in such frame being controlled 55 by stops 27. The frame also provides for the lateral adjustment of the shaft 26, with its cutters, with relation to the frame 21 in any suitable way, such as by the slots 28 in the guide-plates 29, in which the bearings 60 30 for the shaft 26 are mounted to slide. 65

The bearings 30, carrying the shaft 26, are mounted to slide vertically in the guide-plates 29, being supported by the stops 27. These guide-plates having the horizontal slots 28, through which pass suitable holding-bolts, can 70 be adjusted laterally upon the depending frame 21, and so provide for the lateral adjustment of the shaft 26. This is accomplished simply by loosening the bolts in the slots 28 and adjusting the shaft to proper position and again tightening the bolts. When 75 the seats are to be formed at greater or less distances from the rails, this is arranged for by the adjustment of the guide-plates 29, and vertical adjustment of the shaft is provided 80 for through the stops 27. In the construction shown the cutter-shafts are coupled, by means of the rods 31, with the swinging shaft 32, from which the chains or belts 24 25 pass around suitable pulleys or sprocket-wheels to 85 transmit the power from the engine to the cutter-shaft 26, and a suitable lever 33 is provided to raise and lower the cutter-shaft, such lever being connected with the straps above referred to. The cutters shown are adapted 90 to cut not only the kerfs 4 in the ties, but also to cut the rail-seats 3 in the surface thereof, the rotating cutters being provided with suitable knives 37 38 on its periphery for that purpose. The knives of the cutter-wheels 95 can of course be changed, as desired. For example, the knives may be formed to cut simply plain-faced seats on the ties to receive the ordinary flat-bottomed rails or to receive tie-plates adapted to support the rails or they 100 may be arranged, as shown, to cut the seats and kerfs. For some purposes it is also desirable to mark lines on the ties to indicate the exact alinement of the rails when they are to be shifted into temporary position for 105 the purpose of forming permanent seats on the ties in the positions previously occupied by the rails. For this latter purpose markers 39 may be employed, being illustrated as circular toothed wheels secured to a separate 110 shaft mounted in the depending frame, to mark an exact line the proper distance from one or both rails to provide for the shifting of the same into temporary position. 115 In the use of the invention where the track is to be resurfaced or supported base-bars or new rails having downwardly-projecting ribs are to be substituted for the old rails the custom is to clear away the ballast, so that the cutters will not strike the same, and to pass 120 the cutting apparatus along the rails, cutting temporary seats for the rails without having kerfs formed at the base thereof or simply marking lines on the ties for the shifting of the rail through the marker 39. The rails 125 are then shifted into their temporary position and spiked to place, and the cutters for forming the permanent seats in the ties are adjusted, the height of the same being arranged by the stops 27, and their proper po- 130

sition with relation to the rails being provided through the side adjustment of the guide-plates 29, and, if necessary, kerf cutters or knives 37 being arranged on the cutter-wheels. The car is again passed along over the track, being either fed forward by its own engine or pushed by a suitable power or hand means, and through the connections the cutter-shaft is rotated, and the seats or 10 seats and kerfs are cut in the ties in position to receive the permanent track. Where the object is simply to plane new seats for the rails or for tie-plates to receive the same, after cutting such seats the rails are reshifted 15 into place either into the seats or onto the tie-plates resting in seats and spiked to place. Where the supporting base-bars of said application Serial No. 131,918 are employed, these base-bars are seated in the ties, and the 20 rails are shifted into position upon the same, the outer edges of the flanges fitting against the upwardly-extending ribs of the base-bars, and they are spiked to place. Where the object is to provide for the seating of rail structures having depending supporting-ribs, as 25 in said application Serial No. 131,919, the new rails are seated in the ties and secured in place and the old rails removed from their temporary seats. Where bridge-pieces are 30 to be arranged simply under the rail-joints, as in said application Serial No. 131,920, the best practice is to unspike the rails from the ties on which the bridge-pieces are to be located and draw the ties out from under the 35 rails and to carry the apparatus along the track and lower down the cutter-shaft, with its cutters, so as to cut the seats or the seats and kerfs in the ties so shifted, and then to put the bridge-pieces in place and shift them 40 under the rails and respike them.

In any such use of the apparatus it provides a very simple and efficient means for cutting the seats or kerfs in the ties and reduces the cost of changing or relaying track, while providing for the accurate cutting of such seats both as to the depth of the same and their alinement with the track, since the cutting apparatus is guided through the rails, and where the rails are in proper alinement the 45 like alinement of the track itself is assured and with work can be done cheaply and quickly. In the use of the apparatus it is evident that where the tracks are curved it is necessary to so construct the cutting apparatus that the rotating cutters or the markers will follow exactly the curves of the track. If the car-body were continuous and supported on trucks at the ends and the cutting apparatus were suspended between the same, in 55 the swinging of the car-body the cutting apparatus would be drawn out of proper alinement with the rails, and therefore the seats cut would not conform exactly to the curves of the rail; but by dividing the car-body 60 and providing it with a pivotal connection

while proper support for the apparatus is obtained the cutting apparatus is enabled to follow exactly the curves and bends of the track and in that way to provide for cutting seats at proper distances apart at proper distances 70 from the rails on which the car is supported and at proper height, so that while the work is done quickly and cheaply proper alinement of the rails laid in the seats is assured.

What I claim as my invention, and desire to 75 secure by Letters Patent, is—

1. In apparatus for cutting seats in cross-ties, the combination with the rails and cross-ties, of a supporting-frame formed of a car provided with trucks and a body portion formed 80 of two sections pivoted between the trucks, a guiding-frame between the trucks engaging the rails and cutting mechanism guided by said frame and formed to cut seats in the cross-ties.

2. In apparatus for cutting seats in cross-ties, the combination with the rails and cross-ties, of a supporting-frame formed of a car provided with trucks and a body portion formed 85 of two sections pivoted between the trucks, a guiding-frame between the trucks engaging 90 the rail and cutting mechanism guided by said frame, power apparatus mounted on the car-body and connections therefrom to the cutting mechanism, and connections from said power apparatus to drive the car. 95

3. In apparatus for cutting seats in cross-ties, the combination with the rails and cross-ties, of a supporting-frame formed of a car provided with trucks and a body portion formed 100 of two sections pivoted between the trucks, a guiding-frame between the trucks provided with a guiding-wheel for the cutting mechanism having flanges engaging the rail, and cutting mechanism guided by said frame.

4. In apparatus for cutting seats in cross-ties, the combination with the rails and cross-ties, of a supporting-frame formed of a car provided with trucks and a body portion formed of two sections pivoted between the trucks, a guiding-frame between the trucks provided 110 with one guiding-wheel for the cutting mechanism having flanges engaging the rail, and cutting mechanism guided by said frame, and another wheel provided with a plain face resting on the rail. 115

5. In apparatus for cutting seats in cross-ties, the combination with the rails and cross-ties, of a car carrying a depending frame, having a guide-wheel engaging the rail and having vertical guideways thereon, bearings mounted 120 in said vertical guideways and a rotary cutter-shaft mounted in said bearings and carrying rotary cutters formed to cut the seats in the cross-ties.

6. In apparatus for cutting seats in cross-ties, the combination with the rails and cross-ties, of a car carrying a depending frame, having a guide-wheel engaging the rail and having vertical guideways thereon, bearings mounted 125 in said vertical guideways and a rotary cutter- 130

shaft mounted in said bearings and carrying rotary cutters formed to cut the seats in the cross-ties, said guideways being laterally adjustable on said frame.

5 7. In apparatus for cutting seats in cross-ties, the combination with the rails and cross-ties, of a car carrying a depending frame, having a guide-wheel engaging the rail and having vertical guideways thereon, bearings mounted 10 in said vertical guideways, a rotary cutter-shaft mounted in said bearings and carrying rotary cutters formed to cut the seats in the cross-ties, and adjustable stops at the base of said guideways to regulate the height of the 15 cutter-shaft.

8. In apparatus for forming seats in cross-ties, the combination with the rails and cross-ties, of a supporting-frame and guiding mechanism carried thereby and engaging with the

20 rail, and a marker carried by said frame to form continuous marks on the ties for the adjustment of the rails thereto.

9. In apparatus for cutting seats in cross-ties, the combination with the rails and cross-ties, of a car provided with a depending frame 25 having a guide-wheel engaging with the rail, a cutter-shaft mounted to slide on said frame, a motor, an intermediate shaft connected to said cutter-shaft by means of straps, and power connections from the motor through said intermediate shaft to the cutter-shaft, and a lever for raising the cutter-shaft.

In testimony whereof I, the said WILLIAM GOLDIE, have hereunto set my hand.

WILLIAM GOLDIE.
